UNITED STATES PATENT OFFICE

LOUIS DAVIDSON, OF NEW YORK, N. Y.

LONG SPAN BUILDING AND ARCH CONSTRUCTION

Application filed May 1, 1924, Serial No. 710,385. Renewed September 28, 1931.

My invention relates to improvements in long span arch construction and to buildings comprising such arches, and its object is to use economically the space between the horizontal tie or spring line and the arch proper in a building comprising such arches, and to build roof arches economically; also to eliminate the expensive shop and field work incidental to fabricating and constructing arches, and to use standardized parts of extremely simple design and construction so that the work can be done successfully by unskilled labor with assured accurate results instead of the customary high priced mechanics now ordinarily employed.

The embodiments of the invention are illustrated in the accompanying drawing in which—

Fig. 1 is a sectional elevation of a building with the arch tie rod below the finished floor, showing the use of my arch;

Fig. 2 is an elevation of shoe 1 and does not show the roofing;

Fig. 3 is a transverse section of Fig. 2 on line 3—3, in the direction shown;

Fig. 4 is another transverse section of Fig. 2 on line 4—4 in the direction shown indicating a modification of Fig. 3;

Fig. 5 is an elevation of shoe 1 used where a subsegment 7 is introduced to increase the vertical clearance at the springline of the arch;

Fig. 6 is a transverse section of Fig. 5 on line 6—6;

Fig. 7 is a sectional elevation of a building of the type shown in Fig. 1 showing the manner in which a balcony may be disposed between the floor and arch sub-segment.

Similar numerals refer to similar parts throughout the several views.

The connecting shoe is marked 1, and is preferably but not necessarily a casting into which arch segments 2 are placed. The shoes 1, as shown, are formed with relatively deep sockets 9, and the ends of the segments 2 are adapted to be inserted into said sockets. 3 is the tie rod to resist the horizontal thrust of the arch.

4 are conventional turnbuckles. 5 are beams to support the roof between the arches and deliver the loads to them. 6 is the roof

sheathing and roofing support. 7 are sub-segments, the ends of which are supported by the arches and by the enclosing wall of the building. 8 are machine screws that engage through the shoe wall and firmly bear against the arch segments to take up the slack between the shoe and segment and prevent movement. 9 are the sockets of shoes 1. 10 are walls for delivering the stress from an end face of one segment to an end face of another. 11 are steel bearing plates against which machine screws 8 bear and are used to prevent the screws from biting into the segment. 12 are lugs on the shoes for the purpose of connecting roof beams 5. 13 are seats on the sides of the shoes for the purpose of receiving and holding roof beam 5. 14 is the finished floor of the building. 15 are the side walls of the building. 22 are holes in the shoe walls for the purpose of reducing the weight of the shoe where there is ample bearing surface and strength. 23 are diaphragms against which the ends of segments bear. These diaphragms also serve to tie the walls of the socket together and increase the strength of the shoe and socket.

Shoes 1 are made strong enough to resist bending in the arch due to loading or erection conditions and takes the place of the usual rigid riveted or bolted connection. The usual riveted or bolted arches are expensive to fabricate and erect, and much time is lost in the process of matching, riveting and bolting. These objections are overcome in this invention and a much stronger structure is obtained by assuring full bearing strength at the joints without depending upon riveted or bolted connections.

To simplify the shop and field work diaphragm 23 is built at right angle to the line of the segment that is to bear against it and thereby only right angle cuts are required at the ends of the segments to make a perfect bearing fit. The opposite sockets on each shoe are at an angle to each other to conform to the curvature of the arch. The walls 10 connecting the sockets can be designed to various shapes and the number of walls connecting two sockets increased, depending on the amount of strain that these walls are to

resist. The walls of the sockets will be stressed only when the arch is in bending and will not be subject to direct compression stresses.

5 Much time is saved in erecting buildings with these arches as the roof can be built immediately following the foundations and arches instead of waiting as is necessary in other types for sidewalls to be erected.

10 Fig. 1 shows the arch built in simple form by bringing the arch reaction directly to the foundation and thereby making unnecessary supporting walls or piers in the walls to carry the heavy arch reactions. Fig. 1 also shows

15 an improvement with the sub-segments 7 connecting the arch to the walls for the purpose of giving increased vertical clearance at the point where the arch meets the floor. The loads on the sub-segments are comparatively

20 small and it is therefore practical to build the side walls of hollow cement or terra cotta blocks, light timber covered with conventional siding or shingles, or brick, depending on local market conditions.

25 Fig. 7 shows a modification of Fig. 1 by using the space between the floor and the arch where the latter meets the floor to carry a balcony around the building. This balcony, as shown, extends beyond the arches and is

30 in part supported thereby.

It is evident from the several figures shown that many modifications can be made, and I do not intend to be understood as limiting myself to the outlines and shapes shown in the 35 drawing. The essential principles of my invention as illustrated in the accompanying drawing may be varied within the limits of the appended claims.

I claim as my invention:—

40 1. A building comprising a plurality of long span arches comprising shoes and segments, a floor at substantially the level of the ends of the arches, supports at the ends of the arches, and arch sub-segments extending 45 from the arches to the supports and bearing on said respective elements, each sub-segment and its complemental segment of the arch being connected to the same shoe.

2. A building comprising a plurality of long span arches comprising shoes and segments, a floor at substantially the level of the ends of the arches, supports at the ends of the arches, and arch sub-segments extending from the arches to the supports and bearing 55 on said respective elements, the end segments of each arch and its complemental sub-segment being connected to the same shoe.

3. A building comprising a plurality of long span arches consisting of straight arch 60 segments, means connecting said segments in end to end relation, a floor at substantially the level of the ends of the arches, supports at the ends of the arches and arch sub-segments extending from the supports and supported in 65 part by the arches through the means connect-

ing the arch segments together and providing a vertical clearance where the arches meet the floor of the building.

4. A building comprising a plurality of long span arches comprising straight segments, means connecting said segments end to end, a floor at substantially the level of the ends of the arches, supports at the ends of the arches and straight sub-segments extending from the supports and bearing upon means connected to said first mentioned connecting means and providing a vertical headroom clearance where the arches meet the floor.

5. A building comprising a plurality of long span arches consisting of straight arch segments connected end to end, a floor at substantially the level of the ends of the arches, supports at the ends of the arches, arch sub-segments extending from the supports and supported in part by the arches through the means connecting the arch segments together and providing a vertical headroom clearance where the arches meet the floor, and a balcony intermediate the floor and the sub-segments, said balcony being supported by the supports and by the arches.

LOUIS DAVIDSON.
